UNITED STATES PATENT OFFICE.

PETER ENGLISH, OF BENTON HARBOR, MICHIGAN, ASSIGNOR OF ONE-HALF
TO GEORGE H. PAINE, OF DETROIT, MICHIGAN.

GAS-PRODUCER.

SPECIFICATION forming part of Letters Patent No. 609,761, dated August 23, 1898.

Application filed May 1, 1897. Serial No. 634,709. (No model.)

To all whom it may concern:

Be it known that I, PETER ENGLISH, a citizen of the United States, residing at Benton Harbor, county of Berrien, State of Michigan, have invented a certain new and useful Improvement in Gas-Producers; and I declare the following to be a full, clear, and exact description of the invention, such as will enable others skilled in the art to which it pertains to make and use the same, reference being had to the accompanying drawings, which form a part of this specification.

This invention relates to gas-producers, and has for its object an improved gas-producing apparatus in which the production of gas can be carried on continuously from either coal and oil or from coal and decomposed steam and oil and in which I am able to make use of a quality of soft coal that has been heretofore found practically impossible to use for the production of gas of this character.

The coal I employ is first divided into very fine powder and is fed as a fine powder continuously or as fast as may be required into the top of a producer-chamber that is kept filled or nearly filled with the incandescent coal, and the apparatus is arranged to introduce air into the mass of incandescent coal in different ways in accordance with the results which are desired. For primary combustion and primary heating of the fixing-chambers the air is admitted into the producer-chamber above the grate above the coal, and also at the time of the primary heating of the fixing-chamber a secondary blast of air is admitted into what I term a "secondary" combustion-chamber and there unites with the products of combustion, adding an additional volume of oxygen to them and producing a second combustion, which is continued during the process of primary heating of the fixing-chamber. After the fixing-chamber has been primarily heated steam is admitted through the same blast-mouths through which the secondary supply of air was admitted, and the steam is directed through the primary or producer chamber, and gaseous products formed by this process are conducted into the fixing-chamber and

there enriched by the introduction of oil and fixed.

I also employ in the fixing-chamber a stack-work or checker-work of bars of iron.

In the drawings, Figure 1 is a sectional elevation showing the furnace and two fixing-chambers. Fig. 2 is a sectional elevation showing it filled with coal to the point to which it is usually kept filled when the producer is in action. Fig. 3 is a plan view of the furnace. Fig. 4 is a section across the top of the furnace at the line where the outlet-flue from the furnace leads to the fixing-chamber.

The furnace is constructed with an iron casting 1, within which is a heavy brick lining 2, divided into chambers and flues, of which the central or producer chamber is indicated at 10. Around the central or producer chamber is an annular chamber 3, spaced from the producer by a partition-wall 2^a. Around the producer-chamber and between it and the secondary combustion-chamber 3 and near the top of the division-wall between these two chambers is a third chamber 4, into which there leads a blast-pipe 5^a from without the furnace. From the chamber 4 there leads downward a number of flues 4^a, each one of which opens into a flue 3^a, which connects the producer-chamber 10 with the secondary combustion-chamber 3. There are a number of these connecting-flues 3^a, and they lead slightly upward from the producer-chamber 10 to the secondary combustion-chamber 3, leaving the producer-chamber at points somewhat above the fire-grate 6, but near the bottom of the producer-chamber and entering the combustion-chamber 3 at the bottom of that chamber. Into the producer-chamber 10 below the grating leads an air-blast inlet 7, and above the grating and preferably almost at the top of the chamber there leads another air-blast opening 5. Out from the top of the central chamber there leads a flue 10^a, the purpose of which is to carry off to the fixing-chamber the produced gases. Out from the top of the annular or secondary combustion-chamber 3 there leads a flue 3^b, the purpose of which is to carry off the products of combustion from the chamber 3 to the fixing-chamber. The two flues 10^a and 3^b

3° unite or lead into a common flue 10^b, that opens into the fixing-chamber. During the first part of their course, however, they are separated by a partition 9, at the end of 5 which there is a wing-valve 9^a, that can be turned at will to close either of the flues 10^a or 3^c, and the valve 9^a is changed in accordance with the results that are to be attained from the combustion of the coal, being placed 10 in one position during the primary heating of the fixing-chamber and in the other position after the fixing-chamber has been heated and when it is being utilized for the purpose of fixing the produced gas.

15 Into the top of the producer-chamber 10 opens the mouth of a coal-chute A, that leads from a hopper B. Between the hopper and the chute is a slide-valve b, that can be opened for the admission of coal and closed after a 20 supply of coal has been delivered into the upper part of the chute A. The upper part of the chute A is a receptacle of capacity sufficient to hold a quantity of coal, and at the lower part of the chute and within it are located 25 a pair of grinding or crushing rolls C C'. All the coal entering the producer-chamber 10 passes between these crushing-rolls and is ground or pulverized to a very fine powder. The rolls are geared together by 30 gearing a' and are actuated by a shaft a² and a driving-wheel a, which receives motion from any convenient source of power.

35 Into the fixing-chamber D, above the checker-work of iron bars 11, is an oil-inlet tube 11^b and an air-blast inlet 11^a, and above the door is preferably a hood, the purpose of which is to convey away products of combustion during the very first part of the firing and heating of the fixing-chamber. A second 40 fixing-chamber E has an air-blast inlet 12^a near the bottom of the checker-work of iron bars leading into that portion of the space which first receives the gaseous products coming from the first fixing-chamber. This second 45 chamber E also has a cover and preferably has above it a hood (not shown in the drawings) to convey away products of combustion during the first part or initial heating of the fixing-chamber. This second chamber 50 E is provided with a gas-outlet 12^b, through which passes out the gas that has been produced, either for use or for scrubbing or cleansing, if desired.

The furnace is provided with the proper 55 ash-pit door 8. The fixing-chambers are preferably constructed in a similar manner to the furnace, with an outer sheet of iron lined with a suitable refractory material.

The process of starting and subsequently 60 producing gas in this furnace is as follows: A sufficient quantity of coal is fed into the producer-chamber 10 and fired. The damper 9^a is turned to close the passage-way 10^a and open the passage-way 3^c. The blast 5 is 65 opened and a blast of air admitted through the coal. The products of combustion now pass into the secondary combustion-chamber

3, and during their progress through the flues 3^a are met by a second or auxiliary blast of air that comes from the blast 5^a through the 70 annular chamber 4 through the several conduits 4^a. The first door 11^c is only allowed to remain open for a short time, while the gases passing into the fixing-chamber are so cool that they will not combine. As soon as 75 the gases passing in are hot enough to combine this door is closed and the door 12^c is opened and remains open until the checker-work becomes heated to the proper heat to fix the gas. As soon as this takes place the 80 valve 9^a is turned to close the passage-way 3^c, the blast 5 is closed, the blast 7 beneath the grate is opened, and steam instead of air is turned in through the blast 5^a. Inasmuch as the only escape for the products of combustion from the furnace is now through the flue 10^a, the steam entering the chamber 4 from the blast 5^a passes down through the conduits 4^a and into the producer-chamber instead of into the second combustion-chamber. The 90 steam passing into the producer-chamber passes up through the incandescent coal and the gases produced mingle with a quantity of free coal-gas from the coking-coal at the surface and pass into the now highly-heated fixing-chamber, where there is thrown into the 95 combined gas a quantity of oil through the oil-pipe 11^b, and it is submitted with the vaporized oil to the action of the highly-heated iron checker-work both in this fixing-chamber and 100 in the second fixing-chamber E, and emerges from the second fixing-chamber E ready to be further treated, but in a proper chemical condition for combustion. The subsequent treatment of the gas in the way of washing it or 105 scrubbing it does not differ from the processes heretofore used. With proper handling of the furnace the action may now be made continuous. If, however, the fixing-chamber should become so cool that it will no longer serve to 110 fix the gas passing through it, the process described for initial heating is repeated or partially repeated by changing the direction of escape of the gas from the producer-chamber and changing the blasts, so as to cause combustion in the second combustion-chamber 115 until the reheating has been accomplished.

120 It will be noticed that the bed of coal from which the gas has been driven off is utilized to heat the fixing-chamber whenever it becomes necessary to reheat that chamber; also, the heat from the coke-bed is used to drive off the gases from the newly-introduced coal. Thus the machine makes its own coke.

What I claim is—

125 1. In a gas-producer the combination of a producer-chamber adapted to be filled with coal, an annular combustion-chamber surrounding the producer-chamber, flues leading from the producer-chamber to the bottom of the annular chamber, inlet-pipes for air or steam leading through the wall between the two chambers and adapted to deliver a supply of air or steam, and means whereby the

air or steam can be directed through either of said chambers, substantially as described.

2. In a gas-producer, the combination of a producer-chamber provided with a suitable blast-inlet and a suitable outlet communicating with both the top and bottom of the producer-chamber, a system of steam or air inlet flues in the wall surrounding the producer-chamber, a valve adapted to direct the air at will either through the producer-chamber or into the outlet from the producer-chamber, substantially as described.

3. In combination with a producer-chamber provided with a suitable blast-inlet and with a common outlet communicating with both the top and bottom of the producer-chamber, an annular chamber arranged to receive a supply of steam, flues leading from the annular chamber into that part of the outlet that communicates with the bottom of the producer-chamber, and a valve arranged in

the common outlet to direct steam either through the producer-chamber or into the outlet therefrom, substantially as described.

4. In a gas-producer, the combination of a producer-chamber, an annular chamber surrounding the producer-chamber and communicating with the producer-chamber near the bottom thereof, an annular steam or air chamber in the wall between the producer-chamber and the annular chamber surrounding the producer-chamber, flues leading from the steam or air chamber and arranged to deliver steam or air into the communicating passages between the producer-chamber and the annular chamber, substantially as described.

In testimony whereof I sign this specification in the presence of two witnesses.

PETER ENGLISH.
